UNITED STATES PATENT OFFICE

JOHN T. CULLEN, JR., OF CLINTON, IOWA

STEAM GENERATOR

Application filed August 4, 1928. Serial No. 297,486.

This invention relates to a steam generator, one of the objects being to provide a device of this character which can be produced at the minimum cost and will afford a large 5 storage space both for steam and water.

A further object is to provide a generator which is economical to operate.

Another object is to provide a steam generator utilizing both water and fire tubes which 10 are mounted in a simple and effective way and can be cleaned readily.

A further object is to provide a generator utilizing superposed grates one of which constitutes a water grate, the products of combustion from both grates being adapted to 15 flow together through the generator.

Another object is to so construct the inner shell of the generator as to eliminate projecting surfaces on which scale and mud might 20 accumulate.

With the foregoing and other objects in view which will appear as the description proceeds the invention resides in the combination and arrangement of parts and in the 25 details of construction hereinafter described and claimed it being understood that changes in the precise embodiment of the invention may be made within the scope of what is claimed without departing from the spirit of 30 the invention.

In the accompanying drawings the preferred form of the invention has been shown.

In said drawings,

Figure 1 is a front elevation of a steam 35 generator embodying the present improvement.

Figure 2 is a section on line 2—2, Figure 1.

Figure 3 is a section on line 3—3, Figure 2.

Referring to the figures by characters of 40 reference 1 designates the outer shell of the generator, this shell being formed preferably of sheet iron or sheet steel shaped to provide a transversely rounded top 2 forming a steam dome provided with an outlet 3 at one or more 45 points. To the ends of the outer shell are

welded, riveted, or otherwise suitably connected water-legs 4 and 5 which open into the space between the shell 1 and the inner shell 6. The sides of this inner shell are straight and converge upwardly, these sides 40 merging at their upper ends through a transversely arched crown portion 7. Thus there is formed between the inner and outer shells side water spaces 8 which gradually increase in width from the bottom to the top and join 45 above the crown portion 7. Horizontal water tubes 9 connect the water-legs 4 and 5 and are supported above the lower grate 10 and the bridge wall 11 located back of the grate. These tubes 9 cooperate to form an 50 upper or water grate. Another series of horizontal water tubes 12 is arranged above the tubes 9, these tubes 12 being secured within the water-legs 4 and 5 as shown. Erected on the tubes 9 and extending upwardly to the 55 tubes 12 is a partition 13 which can be formed of fire brick or of a fire-resisting plastic material. This partition is adapted to be shifted forwardly or backwardly along the tubes to 60 reduce or increase the size of the combustion 65 chambers 14 located between the tubes 9 and tubes 12. The top of this combustion chamber is closed by a cover 15 of fire brick or fire-resisting plastic material laid on the tubes 12 and preferably extending between them 70 above the partition 13. Thus when fuel is burning in the combustion chamber 14, the products of combustion must flow downwardly between the tubes 9 and backwardly over 75 the bridge wall 11. While passing over this fire wall the products of combustion will meet with those products resulting from the combustion of fuel on the grate 10.

For the purpose of facilitating cleaning and repairing the water tubes, removable 85 screw plugs 16 are mounted in the water-legs 4 and 5 in line with the tubes. A fuel door 17 is provided in the front water-leg 5 so that fuel can be delivered into the combustion 90 chamber 14 and another fuel door 18 is lo-

cated between the grate 10 and the tubes 9 within the front water-leg 5 to permit fuel to be placed in the lower combustion chamber. A clean-out door 19 may be provided in the lower portion of the water-leg 5.

That portion of the inner shell above the cover 15 and beneath the rounded top 7 of the shell constitutes a flue 20 whereby products of combustion arising between the tubes 9 and 12 back of the partition 13 will be directed forwardly into the front smoke box 21 which is mounted on the water-leg 5. Fire tubes 22 are secured at their ends in the front and rear water-legs of the generator and communicate with the smoke box 21. These tubes are located above and at the sides of the upper portion of the inner shell 6 and the rear ends of the fire tubes open into a rear smoke box or breeching 23 which, in turn, has an outlet 24 for communication with the stack. The water level in the generator is above the fire tubes 22 but below the tops of the outer shell so that a space 25 is thus formed in the outer shell for the reception of steam generated in the device.

The inner and outer shell and the parts associated therewith can be connected by welding or riveting and are adapted to be supported on a cast metal base 26 or in any other desired manner. Fuel is adapted to be burned on the grate 10 and on the water grate formed by the tubes 9 and, as before explained, the products of combustion will pass between the partition 13 and the bridge wall 11 thence upwardly to the flue 20, smoke box 21, tubes 22, to the breeching 23. The globules of steam generated in the water at the sides and top of the inner shell 6 will escape upwardly between the fire tubes 22 into the space above the water level. The generation of steam will also be facilitated by the use of the water tubes 9 and 12 which, with the surface of the shell 6, and the fire tubes 22, presents the maximum surface for the transmission of heat to the water in the generation of steam.

Importance is attached to the fact that the inner and outer shells are provided with smooth surfaces free of projecting ledges on which mud and scale would otherwise collect. Importance is also attached to the arrangement of the removable plugs 16 whereby the water tubes can be cleaned readily. By having the movable partitions 13 the size of the upper combustion chamber 14 can be increased or reduced according to the work required of the generator.

What is claimed is:

1. A steam generator including an outer shell, an inner shell having upwardly converging side walls, water-legs at each end connected to the shells and opening into the space therebetween, a bridge wall within the bottom portion of the inner shell, a grate adjacent the bridge wall, water tubes above the grate and bridge wall constituting a water

bridge wall, front and rear water-legs connected to the outer and inner shells, a horizontal series of water tubes extending over the bridge wall and lower grate and opening into the water-legs said tubes constituting a water grate, a horizontal series of water tubes within the inner shell above the water grate and spaced from the top of said shell and opening into the water-legs, a vertical transverse partition between the water-legs supported between the series of water tubes, and a cover mounted on the upper series of water tubes extending from the front water-leg to said partition and cooperating with the partition and the water grate to provide an upper combustion chamber, the exhaust gases from said upper combustion chamber flowing downwardly through said lower series of tubes and mixing with the gases from the lower grate, the combined gases overflowing over said bridge wall to a passage connecting with the space above said upper series of tubes, there being an outlet from said space.

2. A steam generator including an outer and inner shell cooperating to provide a water holding space between the sides and tops thereof, the side portions of the space increasing in width upwardly to the top portion, a bridge wall within the lower portion of the inner shell, a lower grate in front of the bridge wall, front and rear water-legs connected to the outer and inner shells, a horizontal series of water tubes extending over the bridge wall and lower grate and opening into the water-legs, said tubes constituting a water grate, a horizontal series of water tubes within the inner shell above the water grate and opening into the water-legs, a vertical transverse partition supported between the series of water tubes, a cover mounted on the upper series of water tubes and cooperating with the partition and the water grate to provide an upper combustion chamber, a chamber above said cover, said combustion chamber having an outlet below said water grate between the partition and the bridge wall, a smoke box outside each water-leg, longitudinal fire tubes mounted in the water space above the inner shell and opening into the smoke boxes, said tubes extending through the upper portion of the space between the shells, that portion of the inner shell above the upper combustion chamber constituting a flue for conducting products of combustion into one smoke box, there being an outlet in the other smoke box.

3. A steam generator including an outer shell, an inner shell having upwardly converging side walls, water-legs at each end connected to the shells and opening into the space therebetween, a bridge wall within the bottom portion of the inner shell, a grate adjacent the bridge wall, water tubes above the grate and bridge wall constituting a water

grate, another set of water tubes above the water tube grate, spaced therefrom and parallel thereto, a partition supported between the upper and lower tubes and movable to
5 vary the size of the combustion chamber above the water tube grate, a cover supported by the upper water tubes for closing the top of said combustion chamber, said chamber and said lower grate having a combined outlet between the partition and the bridge wall.
10

In testimony that I claim the foregoing as my own, I have hereto affixed my signature.
